UNITED STATES PATENT OFFICE.

ERICH H. LICHTENBERG, OF MILWAUKEE, WISCONSIN, ASSIGNOR TO KOEHRING MACHINE COMPANY, OF MILWAUKEE, WISCONSIN.

STOP MECHANISM FOR CONCRETE-DISTRIBUTERS.

1,113,661.

Specification of Letters Patent.

Patented Oct. 13, 1914.

Original application filed October 21, 1912, Serial No. 727,017. Divided and this application filed September 8, 1913. Serial No. 788,742.

To all whom it may concern:

Be it known that I, ERICH H. LICHTENBERG, a citizen of the United States, residing at Milwaukee, in the county of Milwaukee and State of Wisconsin, have invented certain new and useful Improvements in Stop Mechanism for Concrete-Distributors, of which the following is a specification.

10 The present invention appertains to that type of concrete distributing machines described in the Letters Patent of Philip A. Koehring, No. 1,063,268, issued June 3, 1913, and also in my pending application for patent for conveyer apparatus, Serial Number 727,017, filed October 21, 1912.

15 The improvements hereinafter set forth constitute a division of said co-pending application No. 727,017 and embody particularly certain automatic stop mechanism adapted to coöperate with a carriage movable along a suitable supporting boom whereby a dumping bucket sustained by said carriage is adapted to be brought to a stop 25 when the carriage reaches a predetermined position on the boom, in which position the bucket is adapted to be recharged from a mixer or equivalent source of supply.

In carrying out the invention it is contemplated to provide suitable clutch mechanisms, one to control movement of the carriage and bucket in one direction along the supporting boom, and the other to control movement of said parts in an opposite direction on the boom, said mechanisms being manually operable and associated with the stop mechanism hereinbefore mentioned, which mechanism comprises essentially a device adapted to be moved by means on 35 the carriage when the latter reaches a predetermined point in its travel on the boom. The said movable device under automatic actuation of the carriage is capable of shifting the clutch mechanisms which control 40 the movement of the carriage, into a neutral position, the travel of the carriage and bucket being thus discontinued.

45 The automatic stop means is peculiarly designed in that the movable member or device which is operated by the carriage is of somewhat umbrella-like shape so that while it moves up and down and in opposite side directions, with the boom when the latter is adjusted, it nevertheless is always

adapted in whatever position it assumes to engage and actuate the control means for neutralizing the clutch or driving mechanisms.

50 A full understanding of the invention will be obtainable on reference to the description of the details found hereinafter, and to the appended drawings, in which:

Figure 1 is a side elevation of a machine embodying the essential features of the invention; Fig. 2 is a vertical transverse section taken about on the line 2—2 of Fig. 1, looking in the direction of the arrow; Fig. 3 is a detail sectional view of certain parts of the automatic stop mechanism; and Fig. 4 is a detail view of the automatically operated angular arm.

55 Referring to the drawing by numerals, 1 indicates a mixing drum which may be of conventional type and mounted in the usual manner on the truck 2. From the discharge end of the drum 1 extends the discharge chute 3, and the drum is surrounded by a gear 4 which meshes with a pinion 5 fixed to a shaft 6. Upstanding from the truck 2 is a framework 7 and extending rearwardly from the framework 7 are beams 8 formed with bearings for the shaft 6, the said shaft being disposed preferably substantially midway of the width of framing 7, and at its forward end carrying bevel gear 9, which 65 meshes with bevel gears 10 and 11 journaled on shaft 12. Shaft 12 is in turn journaled in bearings 13, 13 supported by forwardly extending brackets 14 fixed to the framing 7. Each bevel gear 10, 11 70 is fixed to a clutch 15 each of conventional type and provided with a power transmitting sleeve keyed to the shaft 12. A link 17 is pivoted at its upper end to one of the brackets 14 and is formed with a collar surrounding the circumferential groove in the sleeve 16 of the clutch fixed to gear 11 and a similar link 18 is pivoted at its upper end to the other bracket 14 and similarly engages the sleeve 16 of the clutch for the 75 gear 10. The lower ends of links 17 and 18 are linked together by a pivotally connected link 19, and one of the pendent links, 17, 18, preferably 17, is provided with an operating handle 20 so that the operator may 80 shift the links 17, 18 in one direction for operatively connecting gear 11 to driving shaft 12 in one direction, or the lever 20

85 90 95 100 105

may be shifted in the opposite direction for operatively connecting gear 10 to shaft 12 for driving the same in the opposite direction, the gear 9 meshing with both gears 10 and 11. Preferably between the gears 10 and 11 a grooved pulley or sheave 21 is fixed to the shaft 12, and lying within the grooves of and wrapped about the sheave 21 is a cable 22 which extends upwardly from the sheave and is passed about a similarly constructed sheave 23 sustained by a shaft 24 journaled in bearings 25 vertically slidingly mounted in brackets 26 fixed to the upper part of framing 7, said bearings 25 being engaged by set screws 27 for adjusting the elevation of the shaft 24 and thereby adjusting the tension of the cable 22.

Bolted or otherwise rigidly fixed to the upright framing 7 is a forwardly extending bracket 28 having an outstanding bearing plate 29 on which is mounted the inner bearing end of a boom 30, the said bearing end of the boom being provided with a worm gear 31 meshing with a worm 32 fixed to a shaft 33 journaled in bracket 28 and carrying a hand wheel 34 for enabling manual swinging of the boom 30 horizontally about its vertical axis, the said boom being pivotally connected to the bracket 28 by a pivot bolt 35 extending through the bearing plate of the boom and the bearing plate of the bracket. Boom 30 preferably consists of an I-beam, as clearly seen in Fig. 2, the inner or rear end of the beam being fixed to a casting 41 constituting the bearing plate of the boom and affording journals for the shafts of pulleys 36, 37 and 38, the pulley 36 being disposed above the upper edge of the I-beam, and the pulley 37 serving merely as a guide, while pulley 38 is disposed with its lower edge below the lower edge of the I-beam, each of the pulleys 36, 37 and 38 being preferably grooved. The cable 22 extends from one side of pulley 23 downwardly and about pulley 36 and thence forwardly or outwardly to the outer end of the boom and is there passed about a guiding pulley 39 journaled in a bracket casting 40 fixed to the outer end of the I-beam, the cable extending thence inwardly along the under edge of the I-beam to and being passed about the pulley 38 and thence about the pulley 37 into substantial alignment with pulley 23 and thence upwardly to and about the pulley 23. The cable 22 may thus be endless in its nature but, as hereinafter pointed out, an ordinary cable is employed having its ends fixed to a moving shuttle to be described.

Extending laterally from the main body 60 of the casting 41 are guiding sleeves 42, 42 in which are slidingly mounted guiding bars 43, 43, to the upper ends of which is fixed a shield or actuating member 44 of somewhat umbrella-like shape. As best seen in Fig. 3, the member 44 extends beneath the link 19,

and fixed to link 17 is an angular arm 45 whose horizontal arm overhangs the member 44, and the free end of said horizontal arm is provided with a pin or bolt 46 adjustable vertically into position for being engaged by the member when the free end of arm 45 is lowered, whereby, when the member is elevated into contact with said lever the arm 45 and connected parts are adapted to be thrown thereby to the neutral position, as hereinafter set forth.

A trolley or bucket carriage 47 is mounted to run on the boom 30, the carriage being preferably provided with flanged wheels 48, 48, journaled on pins carried by upstanding arms of the trolley carriage, the several wheels 48 being mounted to roll upon the lower flanges of the I-beam comprising the boom 30. Bail-like arms 49 are fixed to and depend from carriage 47 and at their lower ends are fixed to and support bucket 50. Journaled transversely in the carriage 47 is a shaft 51 to which are fixed crank arms 52 which are preferably disposed within the planes of the outline of the carriage and beneath the boom, said arms being carried by a sleeve 52" fixed to shaft 51 between the sides of carriage 47. Bucket 50 is of the openable or dumping type, having the bottom doors 50' which are engaged by links 53', 53', said links extending upwardly and being connected to a link 53, the upper end of which is fixed to an arched, rigid link-section 54. Link section 54 extends between arms 52 and has its free end pivoted to the free ends of said arms by pivot pin 55, the rigid link section 54 being arched to extend past shaft 51 for allowing the free upper ends of arms 52 to lie at one side of the vertical plane of the axis of shaft 51 while the lower end of link section 54 lies at the same side of said plane, and an intermediate portion of the link section engages the sleeve 52" at the other side of said plane, arms 52 being thus held by weight against movement in one direction and being positively held by the engagement of link section 54 with sleeve 52" against movement in the other direction.

The shaft 51 extends beyond the trolley carriage 47 at one side and the extension of the shaft carries a trip arm 56 which is limited in the amount of its swing by stops 56', 56' outstanding laterally from carriage 47. The free end of arm 56 is preferably provided with a handle 57 enabling manual manipulation. Extending inwardly from the free end of arm 56, that is, extending in an opposite direction from the handle 57, is a boss 58 which, when the handle is disposed in its forward position, that is when the doors 50' are opened, is positioned for engaging a cam or trip arm 59 depending from a bracket 60 which is fixed to the I-beam of the boom adjacent the inner or

rear end thereof, the arm 59 being disposed to engage the boss 58 just prior to the arrival of the trolley carriage 47 at its innermost position.

5 Since the operation of the cable 22 and control mechanism to cause the discharge of the bucket 50 at a predetermined point in its movement outwardly along the boom 30 is fully presented in my co-pending application above identified, description of this operation is omitted, it being obvious that the cable is fully capable of moving the carriage and its supported bucket 50 back and forth along the boom.

15 As best seen in Fig. 2, the guiding bars 43 are provided, each on its inner face, with plates 74, 74 whose lower edges terminate above the lower guiding eyes 42, and rearwardly extending arms 75 project from 20 and are fixed to carriage 47 and have their inner or rear ends tapered, as at 76, for forming cams adapted to pass beneath the lower edges of the plates 74 for elevating the same and correspondingly elevating all 25 the connected parts, with the result that the shield 44 is elevated when the carriage 47 is moved inwardly from the position seen in dotted lines in Fig. 1 to the position seen in full lines therein, the upward movement 30 imparted to the shield being sufficient for elevating the free end of the angular arm 45 and thus throwing the lever 20 and connected parts to the neutral position whereby the inward movement of the carriage 47 35 is automatically stopped. The peculiar action of the member or stop device 44 as just referred to will be clearly understood on reference to Fig. 2 wherein it will be noted that to cause the inward movement 40 of the bucket 50 on the boom the lever 20 will have been pulled to the right, this action necessarily causing a slight lowering of the inner arm of the lever 45 to assume the dotted line position illustrated in said 45 figure. The raising of the device 44, owing to the impingement of the parts 75 with the parts 43, causes the member 44 to engage the screw 46 of the member 45, thereby elevating the inner arm of the latter and 50 causing a rocking leftward of the links 17, 18 and 19 until the clutches assume their neutral position, thus disconnecting the drive from the carriage and permitting the latter to come to a stop with the bucket 50 55 beneath the chute 3 ready to be recharged with another load of mixed materials. It is to be observed from the structure illustrated that outward movement of the carriage is adapted to be controlled by manual 60 manipulation of lever 20.

The outer or free end of the boom 30 may be sustained in various well known and conventional ways, but by preference the framework 7 pivotally sustains a pair of links 77 in the free ends of which is journaled

a pulley 78, preferably of the groove type, about which is passed a sustaining cable 79, one end of which cable is fixed to a casting 80 which latter is fixed to the forward portion of the boom 30. A windlass 81 is sustained by casting 80 and the opposite end of cable 79 from that fixed to the casting is attached to the windlass so that a portion of the cable is adapted to be taken up or paid out according to the elevation desired 70 for the boom 30, the windlass being provided with a ratchet wheel 82 engaged by a pawl 83 adapted for sustaining the boom in a given adjusted position. A hand wheel 84 or other suitable operating means may 80 be provided for actuating the windlass.

In operation, the parts being in the position indicated in full lines in Fig. 1, as the drum 1 is rotated, the requisite charge of concrete or other matter to be delivered is 85 discharged through chute 3 into bucket 50 and thereupon the operator throws the lever 20 inwardly or toward the left as viewed in Fig. 2, whereupon the sheave 21 is rotated in the direction for hauling in on the portion 90 of cable 22 above boom 30 and paying out the other portion thereof, whereby the carriage 47 is moved outwardly along the boom, and the bucket 50 automatically dumped when the carriage 47 reaches a pre-determined position in the length of the boom 30, as heretofore pointed out. The return movement of the carriage 47 is accomplished by throwing in the other clutch, an action obtained by shifting the lever 20 100 to the right as illustrated in Fig. 2, and described in detail hereinbefore, the bottom doors of the bucket 50 remaining open during the return movement of the carriage until the boss 58 engages cam 59 and causes 105 the arm 56 to elevate the connected parts and thus close the doors. The final closing movement of the doors of the bucket is accomplished as the carriage 47 reaches its position shown in full lines in Fig. 1 and 110 simultaneously for all practical purposes the stop member or shield 44 is raised so as to act on the parts 17, 18, 19 and 45 to neutralize the clutches and stop the movement of the carriage. 115

It will be observed that the arrangement of the trip arm 59 is such that when the carriage 47 is at the inner limit of its movement on the boom 30, the means controlling the openings of the bucket 50 is locked from 120 operation. In other words, in the normal position of the parts of the apparatus, during the process of filling the bucket 50 from the mixer 1, the members 56 and 59 so abut with one another that there is no liability 125 of accidental opening of the bucket since the engagement intermediate the parts 56 and 59 is practically a locking relation until the carriage 47 moves outwardly sufficiently to separate the parts 56 and 59. 130

Since the boom 30 is movable vertically by raising or lowering its outer end, and likewise a lapsed for lateral or horizontal movement, it will be apparent that the member 44 must necessarily be sufficiently large, that, irrespective of whatever position is assumed by the boom on which the member 44 is supported, said member will be adapted to impinge the screw 46 on the arm 45 for a proper operation of the stop mechanism. It is for this reason that the umbrella-like shape for the member 45 is found most satisfactory, being such that the same relative positions of the parts 44 and 46 are maintained whatever position the boom 30 may assume.

Having thus described the invention, what is claimed as new is:—

1. The combination, with a boom and a trolley carriage therefor, of a cable for actuating the carriage, a sheave for driving said cable, oppositely disposed clutches for actuating the sheave, a lever for throwing the clutches, a cam on the carriage, and means actuated by the cam for shifting the lever to a neutral position on the return movement of the carriage.
2. In means of the class described, the combination of a support, a boom mounted for horizontal swinging movement on said support, a carriage movable longitudinally of the boom, operating mechanism for shifting the carriage along the boom, a controlling device for stopping and starting said operating mechanism, automatic stop means operable by the carriage at a predetermined point in the movement of the latter on the boom to actuate said controlling device to stop said operating mechanism, and connections intermediate said stop means and the boom for maintaining the stop means in operative relation to the controlling device irrespective of whatever position is assumed by the boom.
3. The combination, with a boom and a carriage movably mounted thereon, of a cable for actuating the carriage, a sheave for driving the cable, clutch and gear mechanism for driving the sheave, a lever for controlling the clutch mechanism, an angular arm connected with said lever and having an outstanding arm, a shield extending beneath the planes of the outstanding arm, means supporting and guiding said shield, and cams on the carriage extending inwardly therefrom and adapted to engage the supporting means of the shield for elevating the same when the carriage arrives at its innermost position on the boom, the shield being positioned for striking the outstanding arm of the angular arm when the shield is elevated for moving the connected parts to a position releasing the clutch.
4. In means of the class described, the combination of a supporting framework, a

boom mounted thereon, means whereby the boom may be swung in a horizontal plane, a carriage movable lengthwise of the boom, cable driving means connected with the carriage to shift the same back and forth on the boom, a controlling device for said cable driving means, and automatic stop means on the boom comprising a vertically movable member operable by the carriage to be engaged with said controlling device to thereby affect the operation of the cable driving means.

5. In combination, a framework, a boom, means to move the boom on the framework, a carriage movable along said boom, an actuating cable connected with said carriage, means for operating said cable and thereby communicating movement to the carriage, and a stop device operable by the carriage at a predetermined point in its movement to render the cable operating means inactive, said stop device comprising an arm carried by the framework, and a coacting member movable with the boom and maintained in a position to operate said arm in whatever position the boom is arranged.

6. In combination, a boom, a carriage adapted to travel along said boom, a cable for actuating the carriage, cable operating means, a stop device movably mounted at one end of the boom, controlling members for the said operating means, and means on the carriage for moving said stop device into coöperation with the said controlling members whereby to render the operating means inactive at a predetermined point in the movement of the carriage.

7. In combination, a boom, a carriage adapted to travel therealong, a stop device located adjacent to said boom, an actuating cable for the carriage, operating means for said cable, and means intermediate the carriage and the said stop device whereby to move the latter at a predetermined time to render inactive the cable operating means.

8. In combination, a carriage, a support on which said carriage is adapted to travel, an actuating cable for driving the carriage, operating means for said cable, a stop device situated near the carriage support, and means intermediate the carriage and stop device for causing movement of the latter at a predetermined point in the travel of the carriage to render the cable operating means inactive.

9. In combination, a carriage, a support on which said carriage is adapted to travel, an actuating cable for driving the carriage, operating means for said cable, a stop device situated near the carriage support, and means including cams on the carriage to engage the said stop device whereby to move the latter for coöperation with the cable operating means to render the said operating means inactive.

110

105

115

120

125

130

10. In combination, a boom, a carriage adapted to travel therealong, means for driving said carriage back and forth including clutch mechanisms, manual means 5 for controlling said clutch mechanisms, and automatic means for controlling the clutch mechanisms including a stop device and means on the carriage for coöperation with the stop device to cause the latter to neutralize the clutch mechanism for rendering 10 the carriage driving means inactive.

11. In combination, a support, a boom mounted for movement vertically and horizontally on said support, a carriage movable 15 along the boom, driving means operatively connected with the carriage, and automatic stop mechanism including controlling means for rendering said driving means inactive, and a member on the boom for actuating 20 said controlling means irrespective of the position assumed by the boom.

12. In combination, a support, a boom movably mounted on said support, a carriage movable along the boom, cable means 25 connected with the carriage for actuating the same, driving mechanism for said cable, control means for the latter to discontinue its operation, and a member on the boom movable with the latter to its adjusted positions 30 and adapted in any position to coact with said control means for operating the latter.

13. In means of the class described, the combination of a supporting framework, a 35 boom mounted thereon, means whereby the boom may be swung in a horizontal plane,

a carriage movable lengthwise of the boom, cable driving means connected with the carriage to shift the same back and forth on the boom, a controlling device for said cable driving means, automatic stop means on the boom comprising a vertically movable member operable by the carriage to be engaged with said controlling device to thereby affect the operation of the cable driving means, 45 and connecting means supporting said stop member for vertical movement on the boom and maintaining the same in operative relation to the controlling device in whatever position the boom may be adjusted. 50

14. In a machine of the class described, the combination of a support, a boom mounted on the support for horizontal swinging movement, a vertically slidable stop member carried by the inner end of the 55 boom, a carriage on the boom, driving mechanism for moving said carriage back and forth along the boom, a controlling device for said driving mechanism arranged adjacent to said stop member, and means on the 60 carriage capable of engagement with the stop member when the carriage reaches a predetermined point in the length of the boom, whereby the operation of the driving means is controlled from the carriage in any 65 position assumed by the boom.

In testimony whereof I affix my signature in presence of two witnesses.
